UNITED STATES PATENT OFFICE.

JOHN RAPHAEL ROGERS, OF BROOKLYN, NEW YORK, ASSIGNOR TO MERGENTHALER LINOTYPE COMPANY, A CORPORATION OF NEW YORK.

TYPOGRAPHICAL MACHINE.

1,115,110.

Specification of Letters Patent. Patented Oct. 27, 1914.

Application filed August 28, 1911. Serial No. 645,498.

To all whom it may concern:

Be it known that I, JOHN RAPHAEL ROGERS, a citizen of the United States, and a resident of Brooklyn, county of Kings, 5 and State of New York, have invented a new and useful Improvement in Typographical Machines, of which the following is a specification.

My invention relates to typographical machines, and more particularly to that class thereof known to the public under the name "linotype," and illustrated for instance in U. S. Letters Patent to O. Mergenthaler, No. 436,532. In machines of this 10 class, the matrices are stored in a magazine, are released therefrom by the manipulation of the keyboard mechanism, are assembled in line, and are then presented to a mold, wherein the slug or linotype is cast. After 15 this, the matrices are distributed and stored to the magazine from which they started. It is to this restoring or distributing means that my invention specifically relates. In the ordinary form of distributor, 20 the matrices are caused to pass along a grooved rail or bar until they reach the proper magazine channels, into which they drop in the manner well understood in the art. The channel entrances are not located 25 in immediate proximity to the distributor bar or rail, and it sometimes happens that a matrix will not drop directly thereinto, but is displaced or tilted to such an extent that 30 it is caught and held partly above the top of an entrance. This tilting or failure of 35 the matrices to drop directly is caused in several ways, but chiefly by the fact that just at the moment they are released from the grooves of the distributor rail, there is a 40 tendency for them to pivot or swing about their supporting teeth and this tendency is emphasized and increased in the case of the thicker matrices whose teeth are located at one side thereof and consequently well beyond the center of gravity. My improved 45 devices are designed to correct this liability, and to that end I have provided means whereby as the matrix falls the upper part thereof is engaged and guided so as to minimize the tendency to tilt laterally. Preferably 50 I employ a comb-plate formed with projecting teeth between which the upper ears of the matrices pass, and in the form illustrated and described herein this comb- 55 plate is located between two of the distrib-

uter screws and in immediate proximity to the rail or bar. Obviously, however, many changes and variations will suggest themselves to those skilled in the art without departing from the scope of the invention; 60 and generally speaking, I desire it to be understood that I do not limit myself to any specific form or embodiment except in so far as such limitations are specified in the 65 claims.

Referring to the drawings: Figure 1 is a transverse vertical section through the distributing mechanism of a linotype machine, having my invention applied thereto; Fig. 2 is a longitudinal vertical section thereof, 70 taken substantially on the line 2--2 of Fig. 1; and Fig. 3 shows the improved comb-plate detached.

As is usual in linotype machines, the matrices X are provided at their upper ends 75 with sustaining teeth which engage the permuted grooves on the distributor bar or rail A, along which the matrices are fed by the distributor screws B, B, in the customary manner. When the matrix reaches the 80 proper point, it disengages from the bar A and drops into the corresponding channel entrance C. The parts so far mentioned are well known in the art and require no further description. It will be noted that the 85 channel entrances C are not located in immediate proximity to the bar A and that therefore the matrices X have to pass through a considerable intervening space before they 90 enter therin. It is at this point of the operation that the matrix is sometimes displaced or tilted, so that it does not pass cleanly into an entrance C but is lodged and held at the mouth thereof. In order to direct and guide the matrix and to prevent it from falling 95 over laterally, I have devised means to engage its upper portion immediately at the time it drops from the distributor rail. These means are preferably in the form of the bar D formed with lateral and inclined 100 recesses D¹, constituting in effect a species of comb-plate, which I locate between two of the screws B, B, and in such position that the upper ear X¹ of each matrix passes into and is guided by one of the recesses D¹ at the 105 instant it drops from the rail A, as clearly shown in Fig. 1. In this way I minimize the tendency of the matrix to tilt or fall over laterally, so that it will pass properly into the entrance C, it being noted that by guid- 110

ing or restraining the upper portion of the matrix at the moment it leaves the bar A, the effect of gravity is to straighten it or to give it a substantially vertical position during its descent. Not only is this result secured, but due to the inclined form of the recesses D¹, the matrices are also moved edgewise so that their upper ears will not contact with the lower screw B in passing it. It will be further noted that by my improved construction the matrices are properly guided and controlled from the time they leave the distributor rail until they enter their corresponding channels in the magazine entrance or magazine, as the case may be.

Having thus described my invention, its construction and mode of operation, what I claim and desire to secure by Letters Patent of the United States is as follows:

1. In a typographical machine, the combination of matrix distributing mechanism, channels to receive the matrices therefrom, and intermediate extended guides between which the matrices pass, the said guides being arranged so as to engage the matrices before they enter the said channels; whereby the matrices are prevented from falling over flatwise or sidewise in their passage to the channels.

2. In a typographical machine, the combination of matrix distributing mechanism, channels to receive the matrices therefrom, and intermediate vertical guides to engage the sides of the matrices in their passage from the distributing mechanism to the channels, the said guides being arranged to engage the matrices before they enter the channels and of an extent sufficient to maintain their engagement with the matrices until they have passed well within the channels.

3. In a typographical machine, the combination of matrix distributing mechanism, channels to receive the matrices therefrom, and vertically extended guides to engage laterally the upper portions of the matrices, the said guides being arranged so as to engage the matrices before the latter enter the

said channels; whereby the matrices are delivered to the channels in an erect position.

4. In a typographical machine, the combination of matrix distributing mechanism, channels to receive the matrices therefrom, and a comb plate D provided with the vertically elongated recesses D¹ whose opposite extended walls engage the upper ears of the matrices before the latter pass into their receiving channels.

5. In a typographical machine comprising distributing mechanism, the combination of the distributor rail and a conveying screw, with supplemental guiding means located in proximity to the rail and projecting over the screw, whereby the matrix is guided laterally in its descent and also moved edgewise to clear the screw.

6. In a typographical machine comprising distributing mechanism, the combination of the distributor rail and a conveying screw, with supplemental guiding means located in proximity to the rail and projecting over the screw and formed with grooves to engage the matrices laterally; whereby the matrix is guided laterally in its descent and moved edgewise to clear the screw.

7. In a typographical machine, the combination of matrix distributing mechanism, a series of channels to receive the matrices therefrom, and a series of intermediate vertical guides between which the matrices pass, said guides being located in immediate proximity to the distributing mechanism so as to engage the matrices the instant they are released therefrom, and the said guides being extended sufficiently to maintain their engagement with the matrices until they are well within the channels, all for the purpose described.

In testimony whereof I hereunto set my hand this twenty first day of August, 1911, in the presence of two attesting witnesses.

JOHN RAPHAEL ROGERS.
